UNITED STATES PATENT OFFICE.

BENJAMIN S. KOLL, OF SALEM, OHIO.

STOVE-LID.

SPECIFICATION forming part of Letters Patent No. 251,899, dated January 3, 1882.

Application filed June 22, 1881. (No model.)

To all whom it may concern:

Be it known that I, BENJAMIN S. KOLL, of Salem, in the county of Columbiana and State of Ohio, have invented certain new and useful 5 Improvements in Stove-Lids for Cooking-Stoves and the like; and I do hereby declare that the following is a full, clear, and exact description of the same, reference being had to the accompanying drawings, forming a part of 10 this specification, in which—

Figure 1 is a cross-section of my improved stove-lid; and Fig. 2 is a plan view, the center plate being removed.

This invention has relation to stove-lids; 15 and it consists in the novel construction and arrangement of parts, as will be hereinafter fully described, and particularly pointed out in the claims.

The objects of the invention are to provide for 20 the expansion and contraction of the lid and to permit the center plate to be heated uniformly with the rest of the lid; also, to provide the lifter-socket with a ventilating-space, whereby anything that may run or drop into it may 25 be drawn by the current into the fire-chamber of the stove or heater, thereby avoiding the odors and steam that would otherwise be generated were there no ventilation under such circumstances.

30 Referring by letter to the accompanying drawings, A designates the rim of the stove-lid, having the arm B cast therewith and extending to the center of the opening C of the rim, where it is perforated to receive a screw-bolt, D. This 35 arm B begins slightly back of the inner edge, E, of the rim A, and is concave in its upper face for a short distance to form the lower part of the lifter-socket F. Its edges are scalloped or cut away at G from near the perforation H, 40 at the inner end of the arm B, for a short distance to leave a ventilating-space in said socket when the center plate, I, is in place. The center plate, I, is perforated centrally for the reception of the securing-bolt D, and when the

bolt has been passed through the perforation 45 in the plate I and the perforation in the arm B it is secured in place by a nut, K. The central perforation in the center plate is countersunk to receive the head of the bolt, and the edge 50 of said center plate is sufficiently far from the edge of the rim to permit the expansion and contraction of both without danger of cracking them. The center plate, I, where it comes over the arm B, forms the upper portion of the lifter-socket, and causes to be formed the ventilating- 55 space G.

The utility of the invention is obvious, as all parts of the lid may be uniformly heated and cooled, and the socket, having the ventilating-spaces, prevents odors and steam from arising 60 from anything that may have been dropped or spilled into the socket by drawing the same into the combustion-chamber.

I am aware that a two-part stove-lid is not new, and that provision has been made for contraction and expansion in the same to prevent breaking or bulging, and I do not broadly 65 claim the same.

Having thus fully described my invention, what I claim as new, and desire to secure by 70 Letters Patent, is—

1. In a two-part stove-lid, the combination, with the rim A, provided with the arm B, of the center plate, I, perforated centrally and secured to the arm B by a bolt and nut, substantially 75 as specified.
2. In a two-part stove-lid, the combination, with the rim A, having the arm B, concave for a portion of its length, cut away at its edges, and perforated near its inner end, of the center plate, I, secured to the arm B by bolt and nut to form the ventilated lifter-socket, substantially as specified.

BENJAMIN S. KOLL.
